UNITED STATES PATENT OFFICE.

EVERETT P. STROUP AND WILLIAM A. COOK, OF MARION, INDIANA, ASSIGNEES TO MARION MACHINE, FOUNDRY & SUPPLY COMPANY, OF MARION, INDIANA, A CORPORATION.

SOOT BLOWER.

Application filed November 2, 1923. Serial No. 672,269.

This invention relates to soot blowers for boilers having tubes therein, upon which tubes accumulate dust and the like resulting from the passage of hot gases therearound and the deposit of the fine ash and soot thereon. The purpose of the soot blower is to remove said deposit from the boiler tubes, so that the actual transfer of heat will occur in the shortest possible time, that is, by 10 clean tubes.

The invention relates particularly to the head of a soot cleaner and specifically to those of the blower type wherein a fluid is utilized for blowing purposes and generally 15 under considerable pressure. Heretofore it has been extremely difficult to secure a blower head which will supply fluid under pressure to the blowing tube and permit rotation or oscillation of the latter without 20 providing fluid tight joints therefor, which invariably caused the turning parts to be held against turning, except by the application of great force.

The chief object of the present invention 25 therefore, is to provide a blower head which will permit turning of the movable element and the supplying of fluid under pressure thereto, yet permit the turning movement to be accomplished with relative ease and free- 30 dom.

Heretofore blower heads have been utilized which have admitted fluid pressure to the end 35 of the same. This creates an axial unbalanced thrust that is objectionable when transmitted to the stationary support.

Another form of blower head creates a 40 nonaxial thrust, which in the movement of the movable parts prevents the use of a fluid tight joint except at the expense of an excessive power application for turning purposes.

Another chief object of the invention is 45 to construct the blower head in such a fashion that the thrust is axial and is balanced.

The chief feature of this invention consists 50 in the blow tube construction, wherein there are a main blow tube not extending appreciably beyond the boiler setting or head plate and an outward blow tube extension in 55 alignment therewith and the two secured together by a screw connection, and said blow tube extension having about midway thereof a peripheral series of steam receiving ports with an outwardly extending collar or shoul- 60 der on said extension tube on each side of the

series of ports, and the outer end of the extension tube being closed. The extension tube is supported by a steam head which extends for the major portion of the length thereof and which is secured to and supported 60 upon the upper end of a fixed steam conduit, so that the extension tube will be maintained in axial alignment with a main blow tube. Said head is formed of two sections 65 surrounding the extension tube and engaging respectively, the shoulders on the two sides 70 of the series of ports so as to prevent lateral displacement of the tube in the steam head and to guide the turning movement of the extension tube therein. The extension tube 75 is mounted in the steam head with suitable packing at each end of the steam head to make the same steam tight and yet permit the turning movement of the blow tube construction. The steam head has a steam 80 chamber entirely surrounding the series of ports so as to supply steam to the extension tube to resist axial thrust and leave the extension tube balanced therein for easy rotary movement.

The full nature of the invention will be 85 understood from the accompanying drawings and the following description and claims:

In the drawings Fig. 1 is a side elevational view of the invention and associated parts 90 showing the same incorporated in a boiler setting, the latter being shown in section, together with the blower tube and support therefor. Fig. 2 is an enlarged central longitudinal section of the upper right hand portion of Fig. 1. Fig. 3 is a view of a modified form of the invention, partly in elevation and partly in section. Fig. 4 is an end elevational view of the reduction feature shown 95 in Fig. 3.

In the drawings 10 indicates the wall of a steam boiler construction and 11 indicates boiler tubes in staggered relation with each other as usual. Through said wall extends 100 an opening which contains a tubular wall box 12 having a head plate 13 on its outer end. A blow tube 14 extends centrally through the wall box 13 and its inner end 15 is closed. Said blow tube extends transversely of the boiler tubes 11 and has a number of holes 16 in it containing inward extending nozzles 17, whereby there are no projecting portions on the blow tube 14.

Adjacent the wall 10 a header 18 is locat- 110

ed for supplying steam or other fluid under pressure to the blow tube. The steam passes from header 18 through the upward extending steam pipe 19 and goose neck offset 21 and the passage of steam is controlled by hand operated valve 20. The pipe 19 and offset 21 constitute the steam conduit which is in fixed position, being held in place by the header 18, by the bracket 22 and bar 23, which latter is secured to the head of the wall box.

The blow tube construction as herein shown, includes a blow tube 14 in the boiler construction and an extension tube 29 extends outwardly from wall 10 in axial alignment with blow tube 14 and its outer end is closed by wall 40 and its inner end is connected with the blow tube, by one of said tubes being screwed into the other, as shown.

The outer end of the blow tube construction, that is the extension 29, is supported by a steam head 50 which is formed in two separable sections 41 and 51 secured together by bolts 49 and at the lower end the flange 60 of the steam head is bolted to the flange 61 on the upper end of the steam conduit. One section of the steam head is at one side of a peripheral series of ports 38 in the extension tube 29 and is spaced away from said ports so as to form a steam chamber entirely surrounding the ports. To prevent lateral movement or displacement of the extension tube 29, the sections 41 and 51 of the steam head abut against annular shoulders 39 on and extending around the extension tube, there being one shoulder on each side of the series of ports, substantially as shown.

The extension tube 29 is mounted in the steam head with suitable packing for rendering the same steam tight but permitting the easy turning of the tube. As herein shown, the section 41 of the steam head has a packing recess 42 and is externally threaded at 43. A packing gland 44 is located in said recess and a packing nut 46 is internally threaded to engage threaded portion 43 so that when turned it will force in the gland 44 to form a tight joint. On the opposite side of the series of ports the section 51 of the steam head is similarly recessed at 52 and provided with threaded exterior 53. The packing gland 54 is slidably supported by said construction for tightening the packing 55 when the packing nut 56 moves up the gland 54.

With this arrangement the steam head surrounds the major portion of the extension tube 29 so as to support it and supply steam thereto as above without any relative movement of the extension tube and steam head.

The outer end of the blow tube 14 has a collar 27 with longitudinal slots in its periphery. On the inner end of the extension tube there is a pulley or sheave 26 keyed for turning the tube construction which has in

its hub a slot 31 for a key 32 that extends from shoulder 30 over into engagement with one of the notches 28 in the collar 27 on the blow tube 14 so as to cause the blow tube to turn along with the blow tube extension when the wheel is turned. The key 32 is held in place by the set screw 33 in the hub of the wheel 26. With this construction the actual arrangement of the blow tube with reference to the pulley 26 can be adjusted as desired. The wheel 26 is independent of the steam head 50.

Turning of the tube is limited by means for stopping the rotary movement of the wheel 26. This is done by stop 34 on the wall box head plate 13 and positioned to engage a stop 35 on the pulley 26 which is held in place by a bolt 36 and a nut 37.

In Figs. 3 and 4 of the drawings a modified form of the invention is illustrated, and a description of the similar parts is omitted. In this embodiment the blower head is substantially identical with the blower head previously described, but the pulley 126 is otherwise formed. Herein the pulley support 133 is keyed by the key 32 to the extension tube 29 and the blower tube 14 in substantially the same manner. However, the pulley 126 pivotally supports a gear 127 on the eccentric shaft 140, which gear 127 meshes with a gear 128, said gear being maintained stationary by the stop 129 engaging the stop 130 carried by the wall box 13. Engagement with the gear 128 by the gear 127, in the rotation of the pulley 126, causes the pinion 131 also mounted on the eccentric shaft 140, to engage the teeth 132 of the support 133 of the pulley. Thus, the inner pulley part or support 133 rotates at a slower rate than the peripheral or sheave portion 126 thereof, and thus a gear reduction is secured by the foregoing arrangement.

The invention claimed is:

1. A soot blower mechanism including the combination of a wall box head plate in a steam boiler, a rotatable blow tube mounted therein and extending slightly beyond said head-plate, a blow-tube extension removably connected with the outer end of said blow tube and extending outwardly therefrom and in alignment therewith, so that the blow tube and said extension are rotatable as a unit, said extension tube being closed at its outer end and intermediate its ends having a peripheral series of inlet ports and an outwardly radially extending shoulder at each side of the series of inlet ports, a stationary valve controlled steam conduit, a steam head mounted on and carried by said steam conduit and surrounding the blow tube extension and spaced from the series of ports therein so as to furnish a steam chamber surrounding the ports, said steam head being formed of separable end portions secured together with one of said end portions sur-

rounding the blow tube extension at each side of the series of ports and adjacent to the shoulder of the blow tube extension, and packing means surrounding the blow tube
5 extension for providing a steam-tight mounting thereof in said steam head, whereby the blow tube extension is supported by said steam head and proper alinement maintained between the blow tube and its extension and
10 said extension is balanced in said steam head against steam pressure and said steam head and extension prevented from any relative lateral displacement.

2. A soot blower mechanism substantially
15 as set forth in claim 1, a pulley mounted on said blow tube extension near the inner end thereof, means for turning said pulley, and means extended from the pulley into engage-

ment with the blow tube for transmitting power to the blow tube and causing it to 20 turn with the pulley and extension tube.

3. A soot blower mechanism substantially as set forth in claim 1, with a pulley secured on said extension tube, means for turning the pulley, a collar secured around the outer end 25 of the blow tube peripherally slotted, and a removable key adapted to extend from the pulley into one of the slots of said collar, whereby the angular relation of the blow tube and extension tube may be readily ad- 30 justed.

In witness whereof, we have hereunto affixed our signatures.

EVERETT P. STROUP.
WILLIAM A. COOK.
